US00D328283S

United States Patent [19]

Strand

[11] Patent Number: Des. 328,283

[45] Date of Patent: ** Jul. 28, 1992

[54] ELECTRICAL CLIP FOR THE LEAD WIRE
OF A MEDICAL ELECTRODE

[75] Inventor: Jerome E. Strand, Hudson, Wis.

[73] Assignee: Minnesota Mining and
Manufacturing Company, St. Paul,
Minn.

[**] Term: 14 Years

[21] Appl. No.: 502,656

[22] Filed: Apr. 2, 1990

[52] U.S. Cl. D13/149; D13/133;
D24/168

[58] Field of Search D13/133, 146, 147;
D24/168, 187; 439/345, 347, 372, 370, 725, 836,
492, 447, 449; 128/640

[57] CLAIM

The ornamental design for an electrical clip for the lead wire of a medical electrode, as shown and described.

DESCRIPTION

FIG. 1 is a front and upper right perspective view of an electrical clip showing my new design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a front elevational view thereof; and,

FIG. 7 is a bottom plan view thereof.

FIG. 1

FIG. 7

FIG. 4

FIG. 3

FIG. 2

FIG. 5

FIG. 6
